GARRETTSON SMITH AND HENRY BROWN, OF PHILADELPHIA, PENNSYLVANIA, ASSIGNEES
TO ABBOTT AND NOBLE, OF THE SAME PLACE.

Design No. 2,689, dated June 25, 1867; antedated May 28, 1867.

DESIGN FOR THE PLATES OF A STOVE.

The Schedule referred to in these Letters Patent and making part of the same.

TO ALL WHOM IT MAY CONCERN:

Be it known that we, G. SMITH and H. BROWN, of Philadelphia, county of Philadelphia, State of Pennsylvania, have invented or produced a new and original Design for the Plates of the "Caloric" Heating-Stove; and we do hereby declare that the accompanying drawing, and the following explanation thereof, form a full, clear, and exact description of the said design. In the accompanying drawing—

Figure 1 is the lower base-plate of the "Caloric" heating-stove.

Figure 2 the upper base-plate.

Figure 3 the cap.

Figure 4 the front plate.

Figure 5 one of the side plates; and

Figure 6 the door and frame.

The lower base-plate is of the form shown in the drawing, and is bordered by an ornamental edging, *a*, and at the edge of the upper base-plate is an ornamental border, *b*. The cap-plate is oval, has an open ornamental edging, *c*, an opening in the centre surrounded by an annular register-plate, on which is a series of ornamental figures, and on the top of the plate is a series of foliated ornaments, *e*. The front plate *D* has a plain edging, and in each of the two doors hung to the same is a register which is surrounded by ornamental figures. On the edge of the door-frame *F* is an ornamental beading; a beading, *i*, is on the edge of the door, and on the side plates *G* is an ornamental figure of the form shown in the drawing.

We claim—

The design for the plates of the "Caloric" heating-stove substantially as shown in and by the accompanying drawing.

In testimony whereof we have signed our names to this specification in the presence of two subscribing witnesses.

GARRETTSON SMITH,
HENRY BROWN.
